ELECTRIC SIGN

Application filed February 16, 1928. Serial No. 254,663.

This invention relates to an electric sign and has for its object to produce a sign with tubular discharge tube lights which will be free from the structural, electrical and optical defects common to practically all discharge tube signs made heretofore.

In the adaptation of discharge tubes to electric signs many serious difficulties have been met which have resulted in very expensive construction and many limitations in the use of such signs.

In order to be practical discharge tubes must be made in considerable lengths. The characters into which the tubes are formed must therefore be made up in groups of several characters to a tube, covering considerable area on the face of the sign. There are many bends and curves in the tubes and a high proportion of return bends which represents waste. Also it is necessary to paint opaque all portions of the tubes that are merely connecting portions between the characters. The tubes are enormously expensive to make, the efficiency is very low and the liability of breakage so great that the cost of building the sign with the necessary stiffness is often double what it would be with incandescent lights.

The objects of our invention are to provide a sign having a tube with no complicated bends, no opaque portions and in which it is not necessary to provide any extra stiffness to protect the tube from breakage.

In doing this we have accomplished other important results. We have made a sign in which a single tube illuminates both sides of the sign and while being made in the form of a border also serves to illuminate the letters on both sides. That a single tube can thus be made to perform the duty of four tubes seems incredible at first but is easily understood when one realizes the enormous loss in radiation in the signs as they have been made. In addition to the losses due to return bends and opaque portions, there is an additional loss due to the fact that all of the light that

does not go forward from the sign is lost. On account of the high potential of the tubes they must be spaced a distance from the body of the sign. This, and the fact that the tubes jump from letter to letter and to the electrode holes, has prevented the general use of channels. The light is thus scattered, and to maintain the contrast of the letters it is necessary to paint the background a dark color to kill all the light that falls upon it. Even the light that falls upon the letter back of the tube is of little value due to the brilliance of the tube itself. The high brilliance of the tube also has the effect of making the sign unreadable at a distance from which it is distinctly visible.

We have overcome all of these difficulties in our invention by trapping substantially all of the light and distributing it without loss by light colored surfaces. We have in effect reduced the glare of the tube and increased the readability of the letters, without reducing the range of visibility.

The optical system of our sign produces the result of an even distribution of light over a background of considerable width with the exception of the areas adjacent to the letters where the intensity is greatly increased thus giving a very distinct effect of the letters being raised and standing away from the background. Instead of placing the source of light away from the plane of the background as has been the practice in background lighting heretofore we have placed it essentially in the plane of the background, the background of the two sides coming to a sharp edge and the light being split to the two sides of the sign. That we have succeeded in properly illuminating the background with the light in this position is due to the use of the edge reflectors and the use of the back surface of the letters for reflectors.

The open space construction of our sign is necessary for the optical system. It is an

object of our invention to take advantage of this open construction to reduce the wind pressure and lighten the construction, and also to secure the greatest possible clearance of the tube from the metal of the body. While retaining all of the advantages of the open construction it is our further object to secure from all angles of view both day and night the effect of the letters in front of a background and at night the effect of a continuous surface over the entire sign.

The mechanical system of the sign, so far as the tube supporting feature is concerned, is of the semi-rigid type; that is, instead of resisting shocks and strains, it gives before them and minimizes the effect. The background is mounted so that the wind pressure is balanced and the tendency to turn eliminated. This permits us to use a single mounting iron for the background. The tube is mounted so as to give with the background and it is one of our objects to provide a semi-rigid sign construction in which the tube is so mounted that the sign can give under strains without putting any strain upon the tube. It is a further object to provide a construction in which the tube does not stand away from the background subject to breakage but is protected from all sides and may be shipped with the sign and erected without danger.

It is a further object to provide a discharge tube sign that can be manufactured to a standard type and may have the reading matter changed without changing the tubes.

It is another object to make a sign in which a tube having few bends is used and in which the tube can be quickly replaced.

Other desirable objects are secured in our invention as will be apparent from the following specification.

In the drawings, Figure 1 is an illustration of an embodiment of this invention showing one side of a double faced, vertical sign.

Figure 2 is perspective of a portion of the sign shown in Fig. 1 to illustrate the relation of the parts.

Figure 3 is a cross sectional view of the sign shown in Fig. 1 on the line 3—3.

Figure 4 is a cross sectional view of the sign shown in Fig. 1 on the line 4—4.

Figure 5 is a horizontal cross sectional view of a modified form of this invention.

Figure 6 is a horizontal cross sectional view of a single faced vertical sign made according to this invention.

In the drawings the same numeral applies to the same part throughout. Numeral 1, Fig. 1, indicates a double faced vertical sign made according to this invention. 2 and 3 are side reflectors and 4 and 5 are top and bottom reflectors. The four reflectors are faced inwardly and make up the frame of the sign. They may be of any desired shape, but in this case they are shown as channels. For the

purpose of more efficiently directing the light they may be made in the form of a curve as shown in Fig. 5.

6 and 7 are background surfaces of sheet iron. They are convexed and fastened together at the edges 8 and 9. The channel iron 10 passes between them and is secured to them by any suitable means. The channel iron 10 is held to the upper hanger iron 11 by means of the knee 12 and to the lower hanger iron 13 by the knee 14. The sign is supported to the wall by the hanger irons. This construction eliminates the usual framing around the sign as the shape of each element is such as to develop the greatest strength of which it is capable. The construction of the center in particular is very rigid and holds straight and parallel edges for the support of the tube. The tube 15 is secured to the center section by the insulators 15', 15'', etc. The electrodes are close to the center line of the sign. 17 and 18 are the electrodes, 19 and 20 being the offset portions of the tube 15 which hold the electrodes in the proper position to enter the insulating bushings 21 and 22 parallel to each other.

By this arrangement the tube is supported with better clearances from the metal of the sign than by any other construction known. It is possible for the center of the sign to give slightly under wind strains or if struck without the slightest danger to the tube. It is also possible to pack and ship the sign with the tube in place as it is entirely protected by the reflectors. The reflectors also serve as protection to the tube when the sign is in place on the building. This protection is important as tubes are often broken by window washers and by objects thrown from windows. The tendency of the center to move under wind strain is very small as the surface exposed is the same on each side of the center and hence the channel iron need not be heavy.

For signs that are too long for a single tube this construction is modified by adding another set of electrode connections at the bottom. It is also possible for very long signs to break the tubes along the edges and make connections at those points.

The tube 15 lies in the plane of the edges 8 and 9 of the backgrounds, with the exception of the portions at the top and bottom. The offset 16 is provided in the tube at the bottom to clear the iron 10. The letters, 23, 24, 25 and 26 on the near face and 27, 28, 29 and 30 on the distant face are supported from the backgrounds by the pins 31, 31, 31, etc. They are held at a distance from the backgrounds sufficient to effectively serve as reflectors to throw the light back onto the backgrounds, and to be out of the way of the rays cast towards the backgrounds from the side reflectors. The most satisfactory position for the letters is in the planes of the faces of

the sign as defined by the edges 32, 33, 34 and 35 of the side reflectors 2 and 3. In this position no light at all falls upon the face of the letters and a strong contrast exists with the 5 lighted background.

It is found that the effect of the arrangement shown is to cast a halo of light on the background behind the letters causing the letters to stand out in bold relief. By increasing the stroke of the letters this effect is strengthened with the remarkable result that the larger the stroke the better the sign can be read at a distance. This is exactly opposite to the results secured with illuminated 15 letters in which it is necessary to reduce the stroke to secure readability at a distance.

In order to secure the result of the letters always appearing in front of a light surface, the background and reflectors are proportioned as shown in Fig. 3. The line "A—A" 20 indicates the angle of view to the right of which the letters appear in front of the background 6, and to the left of which they appear partly before the background and partly 25 before the inside surfaces of the reflector 3.

In the night when the tube is lighted the space 36 between the background and the reflectors in effect disappears to view and the sign appears continuous from edge to edge. 30 This is due to the fact that the brilliance of the tube in the space is greater than that of any distant light that might ordinarily be seen thru the space. The glare of the tube is greatly reduced, in effect, as compared with 35 luminous tubes as ordinarily used on signs, there being no reflecting background behind the tube. The visibility of the sign is the same as regards distance as tho the letters were lighted with tubes. It becomes readable 40 at a distance from which the other type of sign is still a glare of light.

The cost of maintaining this sign is very small as a tube can be replaced from stock tubes with no delay. The sign can be repainted with the greatest ease.

Fig. 5 illustrates a modified form of reflector designed to more efficiently distribute the light.

Figure 6 illustrates the adaptation of this 50 invention to a single faced sign. 37 indicates the background; 38, the tube; 39 and 40, the side reflectors; 50 the letters, and 51 and 52 the pins for supporting the letters. While some similarity might seem to exist between 55 this construction and the old style of "shadow box" signs heretofore made with incandescent lamps a great difference actually exists both in principle and in results. In the old practice the lights were placed forward and concealed and the letters were placed close to the surface. The result was that the background was lighted strongest near the edges and that light falling on the letters reduced the contrast with the background.

65 The invention is not limited to the herein

particularly described forms but may be modified in various ways within the purview of the following claims.

Having thus described our invention, what we claim as new and novel and desire to secure 70 by Letters Patent is:

1. In an electric sign, a background surface, a light positioned in the plane of said surface and visible from the front of said sign, a reflector positioned on the opposite side of said light with respect to said background surface comprising the border of said sign to reflect radiation from said light to said surface, and opaque characters positioned in front of said background surface. 75

2. In an electric sign, a background surface, a tubular light positioned parallel to and in the plane of said surface, and a reflector on the opposite side of said light with respect to said surface, said light being exposed to view and constituting part of the design of said sign, and opaque characters positioned in front of said background surface. 85

3. In an electric sign, a frame including a reflector, a background structure positioned within said frame and visible from both sides of said sign, and a light between said background structure and said reflector, said light being exposed to view and constituting part 95 of the design of said sign, and opaque characters positioned in front of each of the visible surfaces of said background structure.

4. In an electric sign, a frame including reflectors, a background structure positioned within said frame and spaced therefrom and visible from both sides of said frame, said background structure comprising curved plates joined at the edges thereof and having at least one supporting member extending thru the space therebetween and connecting the said background structure to said frame, said reflectors being positioned to the side of said background structure, characters positioned in front of said background structure 105 on either side thereof, and light radiating means between said background structure 110 and said reflectors.

5. In an electric sign, a frame including a reflector, a background structure positioned within said frame and spaced therefrom and visible from both sides of said frame, said reflector being positioned to the side of said background structure, characters positioned in front of said background structure on 120 either side thereof and a tubular light positioned essentially in the plane of said background structure and between said structure and said reflector.

6. In an electric sign, a frame including reflectors, said reflectors being directed inwardly, a background structure including curved plates joined at the edges thereof providing background surfaces positioned within 125 said frame and spaced therefrom leaving 130

5 a clear space to view between said reflectors and said background surfaces, said background surfaces being visible from both sides of said frame, a light positioned within said frame in said clear space between said background surfaces and said reflectors, said light being visible from both sides of said frame, and characters positioned in front of said background surfaces to intercept radiation from said light and reflect said radiation onto 10 said background surfaces.

11 7. In an electric sign, a convex background surface, a character positioned in front of said background surface and spaced therefrom and means to illuminate said background surface by reflection from the back of said character, said illuminating means being exposed direct to view and positioned adjacent the edge of said background surface.

12 8. In an electric sign, a convex background surface and a tubular light adjacent the edge of said surface, and opaque characters positioned in front of said background surface and spaced therefrom, the relative positions 20 of the several said elements being so related that the portions of said background surface behind the said characters are increased in 25 degree of illumination by virtue of light reflected thereupon from the back of said characters.

9. In an electric sign, a convex surface, a tubular light adjacent the edge of said surface and a character positioned in front of said surface, said light being exposed to view.

10. In an electric sign, a convex surface, a tubular light around said surface and means to reflect light to the portion of said surface most distant from said light, said light being exposed to view.

11. In an electric sign a pair of convexed surfaces joined together with edges meeting and a discharge tube supported from said edges, said light being exposed to view, and characters on said surfaces.

12. In an electric sign, a light colored background, a discharge tube to illuminate said background and opaque characters positioned in front of said background the face of said characters being out of the range of radiation from said discharge tube, said light being exposed to view as a border for said background.

13. In a double faced electric sign, a background structure, characters positioned in front of said background structure, a reflector disposed on the side of said background structure and spaced therefrom, there being a clear space therebetween, a source of light radiation positioned between said background structure and said reflector and visible from both sides of said sign, the dimensions and positions of said background structure, said characters and said reflector being such that from any ordinary point of view 25 said characters appear in front of either said

background structure, said reflector or both said background structure and said reflector.

14. In an electric sign, a reflector structure comprising the frame of said sign, a discharge tube border within said frame and visible from both sides of said sign and a background structure within said border, there being a clear space between said reflector and said background and opaque characters positioned in front of said background structure and so related thereto as to increase the illumination of said background structure by reflection from the back of said characters, the faces of said characters being out of the range of radiation from said discharge tube.

15. In an electric sign, a double faced sign comprising a reflector structure, a background structure therein and means to illuminate both sides of said sign from a single source of light, said source of light being visible from the front of both faces of said sign, and opaque characters positioned on either side of said sign in front of said background surface and out of the range of the radiation from said source of light.

16. In an electric sign, a background surface, a light positioned substantially in the plane of said surface comprising the border of said sign and visible from the front of said sign, a reflector positioned on the opposite side of said light with respect to said background surface to reflect radiation from said light to said surface, and opaque characters positioned in front of said background surface and spaced therefrom, the backs of said characters being light reflecting, and the distance of said characters from said background surface being such that radiation from said light is reflected onto the said background behind said characters thereby rendering the same clearly discernible in silhouette.

17. In an electric sign, a background surface, a tubular light positioned parallel to and in the plane of said surface, a reflector positioned on the opposite side of said light with respect to said surface, said light being exposed to view and constituting part of the design of said sign, and opaque characters positioned in front of said background surface, the backs of said characters being light reflecting, said characters being spaced from said background surface, the several said elements being so positioned with respect to each other that a portion of the radiation from said light is directed onto said background surface by said reflector and a portion of the radiation is directed onto said background surface by the reflecting surfaces of the backs of said characters, the background surface being thereby illuminated to a practical degree to such intensity as to render said characters discernible in silhouette.

18. In an electric sign, a frame including a reflector, a background structure positioned

within said frame, there being a clear space between said reflector and said background structure, said background structure being visible from both sides of said sign, a light 5 between said reflector and said background structure in said space, said light being exposed to view from both sides of said sign and constituting part of the design of both sides of said sign, and opaque characters positioned in front of each of the visible surfaces of said background structure and spaced therefrom, the backs of said characters being light reflecting, the relative positions of the several said elements being such that part 10 of the radiation from said light is directed onto each of the said surfaces of the background structure by said reflector and part of the radiation from said light is directed onto said surfaces by the reflecting surfaces of the 15 backs of said characters.

19. In an electric sign, a frame including reflectors, a background structure positioned within said frame spaced therefrom and visible from both sides of said sign, said background structure comprising curved 20 plates meeting at the edges thereof and having at least one supporting member extending thru the space therebetween and connecting the said background structure to said 25 frame, said reflectors being directed inwardly towards said background structure and so related thereto that radiation reflected from the same will reach both sides of said background structure, a tubular light positioned 30 in the space between said background structure and said reflector parallel to and substantially in a plane with the edges of said background structure and visible from both sides of said sign as part of the design of 35 said sign, and characters positioned in front of each side of said background structure and spaced therefrom, the backs of said characters having light reflecting surfaces, the relative positioning of all of said elements being such 40 that a portion of the radiation from said light is directed onto the two sides of said background structure by said reflectors and a portion of the radiation from said light is 45 directed onto the two sides of said background structure from the backs of the characters 50 respectively positioned in front of the same.

20. In an electric sign, a frame including a reflector, a background structure positioned within said frame and spaced therefrom and 55 visible from both sides of said frame, said reflector being positioned to the side of said background structure and directed thereto-wards, there being a clear space therebetween, characters positioned in front of said background structure on either side thereof and spaced therefrom, the backs of said characters having light reflecting surfaces, and a tubular light positioned close to the plane of 60 said background structure and between said structure and said reflector in said clear space 65

and visible from both sides of said sign as a border.

21. In an electric sign, a frame including reflectors, said reflectors being directed inwardly, a background structure including 70 curved plates with the concaved sides thereof turned towards each other and the edges meeting, said structure being positioned within said frame and spaced therefrom leaving a clear space to view between said reflectors and said background structure, one of each of the exposed surfaces of said background structure being visible from each side of said frame, a light positioned within said frame in said clear space between said background structure and said reflectors, said light being visible from both sides of said frame, and characters positioned in front of 75 said exposed background surfaces to intercept radiation from said light and reflect said 80 radiation onto said background surfaces.

22. In an electric sign, a convex background surface, a character positioned in front of said background surface and spaced therefrom, and means to illuminate said background surface by reflection from the back of 90 said character, said illuminating means being exposed direct to view and positioned adjacent the edge of said background surface.

23. In an electric sign, a convex background surface, a character positioned in front of said background surface and spaced therefrom, the back of said character having a light reflecting surface, and illuminating means disposed to the side of said character 95 exposed to view as part of the intended visible portion of the sign and so located as to cast radiation on both said background and the back of said character, the intensity of illumination of said background in the region behind said character being increased by virtue 100 of the radiation reflected upon it from the back of said character, said region being of greater extent than the area covered by said character whereby the contrast of said character with said background is increased.

24. In an electric sign, a convex background surface, a tubular light adjacent the edge of said surface, and opaque characters positioned in front of said background surface and spaced therefrom, the backs of said characters having light reflecting surfaces, the relative positioning of the several said elements being such that the intensity of 115 the illumination of the portions of said background surface behind the said characters is increased by virtue of radiation reflected upon them from the backs of said characters.

25. In an electric sign, a background member having a convex light reflecting surface, 120 a tubular light adjacent the edge of said surface, and an opaque character member positioned in front of said surface and spaced therefrom, the back of said character member having a light reflecting surface, the rel- 125 130

ative positioning of all of said elements being such that light reflected from the back of said character member upon said convex surface reenforces light cast directly upon said convex surface by said tubular light, the total illumination upon said convex surface being such that the character member is clearly discernible in silhouette thereupon, the light reflected by the back of said character member serving to compensate for the uneven distribution of light upon said convex surface by direct radiation from said source.

26. In an electric sign, a convex surface member, a tubular light around the surface of said member and means to reflect radiation to the portion of said surface most distant from said light, said light being exposed to view.

27. In an electric sign, a pair of convexed surface members joined together with edges meeting and a discharge tube supported from said edges, said light being exposed to view, and characters on the exposed surfaces of said members.

28. In an electric sign, a light colored background, a discharge tube to illuminate said background and opaque characters positioned in front of said background, the faces of said characters being out of the range of radiation from said discharge tube, said discharge tube being exposed to view as a border for said background.

29. In a double faced electric sign, a background structure, characters positioned in front of said background structure, a reflector disposed on the side of said background structure and spaced therefrom, there being a clear space therebetween, a source of light radiation positioned between said background structure and said reflector and visible from both sides of said sign, the dimensions and relative positions of said background structure, said characters and said reflector being such that from any ordinary point of view said characters appear in front of either said background structure, said reflector or both said background structure and said reflector.

30. In a double faced electric sign, a reflector structure comprising the frame of said sign, the reflectors being directed inwardly, a light reflecting background structure within said frame exposed to view on both sides of said sign, there being a clear space between said background structure and said reflectors in which clear space is positioned a discharge tube, said discharge tube being exposed to view on both sides of the sign as a border for said sign and so located with relation to the other said elements that a portion of the radiation therefrom is cast upon both sides of said background structure, and opaque character plates positioned in front of each side of said background structure and spaced therefrom, the backs of said character plates having light reflecting surfaces, said plates being so po-

sitioned with relation to the other said elements that radiation redirected by the said reflecting surfaces onto the surfaces of said background structure reenforces the aforesaid portion of the radiation from said discharge tube and compensates to a measurable degree for the unevenness thereof, the faces of said character plates being out of the range of direct radiation from said discharge tube.

31. In an electric sign, a double faced sign comprising a reflector structure, a background structure therein and means to illuminate both sides of said sign from a single source of light, said source of light being visible from the front of both faces of said sign, and opaque characters positioned on either side of said sign in front of said background surface and out of the range of the radiation from the said source of light.

32. In an electric sign, a light colored background surface, characters positioned in front of said background surface and spaced therefrom, the backs of said characters having light reflecting surfaces, and a source of radiation in the form of a border for said sign visible from the front of said sign and so positioned as to illuminate the said background surface partly by light radiated directly thereupon and partly by light reflected from the backs of said characters.

33. In an electric sign, a reflecting background structure, a reflector disposed to the edge of said background and directed there-towards, a tubular light disposed to the edge of said background and close to said reflector and exposed to view as a border for said sign, an opaque silhouette display member positioned in front of said background surface and spaced therefrom, the back of said member having a reflecting surface, the relative positions of the several said elements being such that radiation from said light redirected onto said background from the back of said silhouette display member reinforces those portions of the radiation cast upon said background directly by said light and reflected upon said background by said reflector, the illumination thus produced upon said background being of increased intensity around the edges of said silhouette member by virtue of that portion of the radiation reflected upon said background by said member.

34. In an electric sign, a reflecting background structure, a tubular light disposed to the edge of said background and exposed to view as a border for said sign, an opaque silhouette member positioned in front of said background surface and spaced therefrom, the back of said member having a reflecting surface, the relative positions of the several said elements being such that radiation from said light redirected onto said background from the back of said silhouette member re-

enforces the radiation cast upon said background directly by said light, the illumination thus provided upon the said background being of increased intensity around the edges of said silhouette member by virtue of that portion of the radiation redirected thereby.
